UNITED STATES PATENT OFFICE.

JOHN B. McDONALD, OF EAST LIVERPOOL, OHIO.

DESIGN FOR A HOLLOW CHINA TABLEWARE ARTICLE.

55,067.

Specification for Design.

Patented May 4, 1920.

Application filed July 11, 1919. Serial No. 310,285. Term of patent 7 years.

To all whom it may concern:

Be it known that I, JOHN B. McDONALD, a citizen of the United States, residing at East Liverpool, in the county of Columbiana and State of Ohio, have invented a new, original, and ornamental Design for a Hollow China Tableware Article, of which the following is a specification, reference being had to the accompanying drawing, forming part thereof.

The invention comprises an ornamental design having the configuration and characteristics delineated and, as shown, is embodied in a neat casserole, but it is contemplated that the design may also be em-

bodied in covered dishes, creamers, sauce boats with or without a fast stand, sugar bowls, teapots, sauce tureens, oyster tureens, and other analogous articles of hollow ware.

In the accompanying drawing showing my ornamental design, Figure 1 is a plan view. Fig. 2 is a view in elevation, and Fig. 3 is a sectional view.

I claim:

The ornamental design for a hollow china tableware article, as shown.

JOHN B. McDONALD.
